UNITED STATES PATENT OFFICE.

CHARLES J. ROSS, OF OAKLAND, CALIFORNIA.

DESIGN FOR A DOLL.

Application filed April 19, 1922. Serial No. 1,845. Term of patent 3½ years.

To all whom it may concern:

Be it known that I, CHARLES J. Ross, a citizen of the United States, residing at Oakland, county of Alameda, State of California, have invented a new, original, and ornamental Design for Doll, of which the following is a specification, reference being had to the accompanying drawings, forming part thereof.

Fig. 1 is a view in front elevation.

Fig. 2 is a view in side elevation.

I claim:

The ornamental design for a doll, as shown.

CHARLES J. ROSS.
